WEB SPLICING DEVICE

**Henry A. Wise Wood, New York, N. Y., assignor
to Wood Newspaper Machinery Corporation,
New York, N. Y., a corporation of Virginia**

**Application November 12, 1932, Serial No. 642,352
Renewed December 4, 1934**

10 Claims. (Cl. 242—58)

The principal objects of this invention are to provide means whereby the running web is relieved of the strains incident to bringing the fresh web roll from a lower to a synchronous speed in a very short time in combination with means for automatically running the same roll through a friction member at a speed less than that of the web to produce the necessary tension immediately after splicing; to provide means for 5 the calibration of the speed-setting device for the rotation of the fresh web roll in such a manner that, just prior to and during the moment of splicing, said fresh roll will be driven at exactly web speed, or very slightly faster, and immediately after splicing the ratio of the variable 10 speed device will be changed so that the same roll, which is now attached to the web, is driven at a speed a little less than that of the web; and to adapt the invention particularly to a splicing 15 machine in which the fresh web roll is driven through power applied to the central axis. 20

Other objects and advantages of the invention will appear hereinafter.

Reference is to be had to the accompanying drawings, in which

Fig. 1 is an end view of a web roll supporting mechanism with a preferred embodiment of this invention shown as applied thereto and showing the splicing mechanism in the act of completing 30 the splice and severing the web;

Fig. 2 is an enlarged view of the electric disconnecting means on the brush supporting arm showing the contacts open;

Fig. 3 is an enlarged view similar to Fig. 1;
Fig. 4 is a front elevation of the same;

Fig. 5 is a plan of a portion of the same

Fig. 5 is a plan of a portion of the same instruments, showing the operating roller in contact with the paper roll;

Fig. 6 is a sectional view on the line 6—

Fig. 7 is a plan of the transmission shown in Fig. 1;

Fig. 1. is a plan of the transmission of

Fig. 8 is an end view of this transmission. The invention is shown as applied to a web

45 splicing mechanism which is the subject matter of my prior application for patent, Serial No. 591,077, filed February 5, 1932. The fresh web roll is brought up to speed by the use of a variable speed transmission applying rotative energy to the roll at its central axis. In devices of this kind it is necessary to compensate the speed ratio of the mechanism rotating the roll spindle to calibrate that ratio with reference to roll diameter. Any inaccuracy in this setting results in difficulty for 50 55 if the roll is driven too slowly, a great strain is

put on the web at the time of splicing and after the splice is made, if the splicing roll feeds the web too fast the web is flooded, not only causing inferior printing but often resulting in paper breaks.

This invention is designed to overcome this difficulty by permitting the calibration of a speed setting device so that prior to, and during, the moment of splicing the roll is driven at exactly web speed or slightly faster to relieve the running web of the strains incident to bringing the fresh roll from a lower to a synchronous speed in a very short time. Also through a mechanism operated by the web pressing member the ratio of the variable speed is changed so that the fresh roll, now the running roll, is driven through a friction member at a speed less than that of the web to thereby produce tension on the web.

As in my said application it will be seen that the drive for the incoming roll is obtained from the press through any convenient press driven member such as a roll 96 carrying a sprocket 97. Through a chain 98 and sprocket 99, the latter attached to the input end of the variable speed transmission 100, a drive to the transmission 100 is obtained. This drive may be varied in gear ratio to compensate for the different diameters of the incoming roll, so that the proper driving force may be applied to the center of the incoming roll. From the output side of the variable speed transmission 100, a gear 1 meshes with an idler 2 which in turn cooperates with a gear 3. The gear 3 is secured to a cross shaft 4 on which is also mounted a bevel gear meshing with a bevel gear 6 attached to drive a vertical shaft 7. The vertical shaft 7, at its lower end, carries a bevel gear 9 for meshing with a bevel gear 10 to drive a jack shaft 11 carried by the reel. The other end of this jack shaft carries a pinion 12 meshing with a gear 13 which is secured to and rotates with a large gear 14. The latter is mounted by an anti-friction bearing on a hub of a spider 15. On each of the three spindles mounted in the spider 15, a gear 16 is rotatably mounted to mesh with the large gear 14. A magnetic clutch armature 17 is mounted by a flexible disc to rotate with the gear 16 so that its friction surface may engage with an adjustable braking disc 18 carried on a magnetic clutch 19 which is secured to 50 rotate with a spindle 20. This provides a clutch arrangement between the drive and the spindle, whereby the energizing of the magnetic clutch 19 will connect the spindle 20 to the drive brought in through the variable speed trans-

mission 100 from the press. An electrical selector is provided so that the proper clutch may be brought into operation when it is desired to make a splice.

5 Figs. 1, 3, and 8 show the speed setting mechanism which insures the proper rotational ratio between the press and the incoming roll as the incoming roll is of one or another diameter. The variable speed transmission 100 has a regulating shaft 21 projecting therefrom to which is attached an arm 22, the free end of the shaft 21 being supported by a bracket 23 to insure rigidity. The variable speed transmission 100 is so built that motion of the arm 22 in one direction speeds up the revolutions of the spindle 20 with respect to the press while motion of it in the opposite direction slows down the spindle 20 with respect to the press. The arm 22 is pivoted to a link 24 whose other end is pivotally attached to a bell crank 26. The upper arm of the bell crank 26 is pivotally attached to a movable sleeve 28. The movable sleeve 28 is slidably mounted on an operating rod 30. Springs 31 and 32 are provided on opposite ends of the movable sleeve 28 and are backed up by collars 33 and 34 respectively. Thus at all times either one or the other or both of these springs tends to keep the movable sleeve 28 central. The left hand end of the rod 30 is pivotally attached to an arm 35, the latter being keyed to a shaft 36. An arm 37 is mounted by a feather on the shaft 36 carrying a measuring roller 39 which is rotatably mounted on the arm 37. The roller may contact with the incoming web roll when it is reeled up to position in essentially the same relationship. When the motion of the arm 37 is translated through the shaft 36 to the arm 35, the rod 30 thereby exerts a pressure to move the sleeve 28 to the desired position and through linkages attached thereto to set the transmission 100.

40 The arm 37 carries attached thereto a ratchet segment 40 against which a pawl 41 is pressed by a spring 42. The pawl 41 is pivotally mounted on one end of the bracket 38 and is so connected 45 with arms 43 and 44 that a rotation of an arm 45 in a counterclockwise direction against the pressure of a spring 46 lifts the pawl 41 away from the ratchet 40 to allow the arm 37 to drop. A projection 47, carried one on each arm of the 50 spider 15, presses against a roller 48, which is rotatably mounted on the arm 45, as the reel is moved past it. This contact of the projection 47 and roller 48 for the dropping of the arm 37 is accomplished just before the incoming roll is 55 brought under the roller 39. Thus, as the reel is rotated to the position shown in Fig. 1, the incoming roll has passed underneath the roller 39 and, through the linkages described above, has 60 properly set the variable speed transmission 100. The pawl 41 would ordinarily hold this setting until the next roll is brought up to position, at which time the cycle would be repeated.

65 In addition to the pawl 41, however, there is a second pawl 51 in engagement with the teeth of the segment 40. This pawl 51 is pivoted to a bell crank 52, the other end of which is pivotally connected to the plunger of a solenoid 53. A spring 54 as well as the weight of the arm 37 tend to keep the bell crank 52 in the position 70 shown in Fig. 1. The instant a splice is made, however, the solenoid 53 is energized, thereby rotating the bell crank 52 in a clockwise direction lifting the pawl 51 and thereby pushing the arm 37 up to change the ratio in the vari-

able speed transmission 100 and thereby drive the fresh roll at a slower speed. Since there is a friction clutch on the spindle connecting the fresh roll with this drive it permits applying tension to the paper without breaking it.

5 The type of brush arm used in my above mentioned application is shown here and can be operated in a similar manner. It will be readily apparent that a pair of contacts 55 may be placed on the brush operating arm 56 or any other convenient place so that, when the brush 57 moves forward to contact the running web with the fresh roll, a brush spring rod 58 moves up and thereby closes the contacts 55. They are used to establish a circuit to the solenoid 53. Through 10 the mechanism described above this slows down the paper roll at the instant that it is transferred from a fresh roll to a running roll so that tension may be obtained. Thus, this invention provides for the driving of a roll prior to splicing 15 and especially through power applied to the central axis with means for driving the roll exactly at or slightly above web speed prior to, and at the moment of, splicing, with means for reducing that speed immediately upon splicing to 20 obtain tension on the web and a simple control of the web roll.

25 Although I have illustrated and described only one form of the invention I am aware of the fact that modifications can be made therein by 30 any person skilled in the art without departing from the scope of the invention as expressed in the claims. Therefore, I do not wish to be limited in this respect otherwise than as set forth in the claims but what I do claim is:—

35

1. In a web splicing mechanism, the combination with means for rotating the fresh web roll, and means controlled by the diameter of said fresh roll for varying the speed of said rotating means to bring the surface speed of the fresh roll substantially to web speed at the time of splicing, of means for reducing the speed of the fresh roll driving means immediately after the fresh roll is spliced to the running web for the purpose of producing tension on the web.

45

2. In a web splicing mechanism, the combination with means for rotating the fresh web roll, means for bringing the surface speed of the fresh roll substantially to web speed at the time of splicing, means whereby the last named means 50 is automatically regulated by the diameter of said fresh roll, and of means for reducing the speed of the fresh roll driving means immediately after the fresh roll is spliced to the running web.

55

3. In a web splicing mechanism for a printing press, the combination with a rotatable member connected with the press to run in proportion to the speed of the press, a shaft connected with the fresh web roll to rotate it through its center, 60 a variable speed transmission for transmitting power from said rotatable member to said shaft, means for controlling said transmission to rotate the fresh roll substantially at web speed at the time of splicing, and means tending to rotate it 65 at a slower speed after splicing.

65

4. In a web splicing mechanism for a printing press, the combination with a rotatable member connected with the press to run in proportion to the speed of the press, a shaft connected with the fresh web roll to rotate it through its center, 70 a variable speed transmission for transmitting power from said rotatable member to said shaft, means engaging the surface of the fresh web roll, and controlled by its diameter, for controlling 75

- said transmission to bring the surface speed of the fresh roll substantially to web speed just before, and at the time of, splicing, means for pressing the running web against the fresh roll to make the splice, and means for then reducing the speed of the roll driving means below web speed to apply tension to the web, said means being operated by the motion of the web pressing means.
5. In a web splicing mechanism for a printing press, the combination with a rotatable member connected with the press to run in proportion to the speed of the press, a shaft connected with the fresh web roll to rotate it through its center, a variable speed transmission for transmitting power from said rotatable member to said shaft, means engaging the surface of the fresh web roll, and controlled by its diameter, for controlling said transmission to bring the surface speed of 10 the fresh roll substantially to web speed just before, and at the time of, splicing, means for pressing the running web against the fresh roll to make the splice, an electric contact on the web pressing means, a solenoid in circuit with 15 the contact and adapted to be energized when the web-pressing means is brought into operative position to make the splice, and means operated by the solenoid for changing the transmission speed to reduce the speed of said roll driving 20 means.
6. In a web splicing device, the combination with a variable speed transmission, mechanism operated thereby for rotating a fresh web roll, and a movable web-pressing means, of an electric contact connected to be closed by the web 25 pressing means when it moves into web pressing position, a solenoid in circuit with said contact to be energized when the contact is closed, and means operated by the solenoid for controlling 30 said transmission to reduce the speed of said roll driving means after splicing.
7. In a web splicing device, the combination with a variable speed transmission, mechanism operated thereby for rotating a fresh web roll, and a movable web-pressing means, of an electric contact connected to be closed by the web 35 pressing means when it moves into web-pressing 40 position, a solenoid in circuit with said contact to be energized when the contact is closed, a lever connected with the solenoid to be operated when the contact is closed, a lever connected with the solenoid to be operated when the solenoid is energized, a pawl carried by the lever, a movable ratchet segment which the pawl is arranged to move when the solenoid is energized, and means operated by the ratchet segment for changing the speed of the transmission to reduce the speed of said roll driving means below web speed to put tension on the web after 45 splicing.
8. In a web splicing device, the combination with a variable speed transmission, mechanism operated thereby for rotating a fresh web roll, and a movable web-pressing means, of an electric contact connected to be closed by the web-pressing means when it moves into web-pressing position, a solenoid in circuit with said contact to be energized when the contact is closed, a lever connected with the solenoid to be operated when the solenoid is energized, a pawl carried by the lever, a movable ratchet segment which the pawl is arranged to move when the solenoid is energized, means operated by the ratchet segment for changing the speed of the transmission to reduce the speed of said roll driving means below web speed, and frictional driving means forming part of the roll rotating mechanism.
9. In a web splicing device, the combination with a rotatable magazine reel having means for rotatably mounting a plurality of paper rolls, driving means for bringing the surface of a fresh roll substantially to web speed, means for effecting contact of the fresh roll and the running web, and means for reducing the speed of the fresh roll driving means subsequent to splicing.
10. In a web splicing mechanism, the combination with a running web and a fresh web roll, of means for rotating the fresh web roll substantially at web speed, means for making a splice, and means controlled by the splice making means for decreasing the speed ratio between the fresh roll driving means and the speed of the web.

HENRY A. WISE WOOD.
